(57) **CLAIM**

The ornamental design for a cylinder, as shown and described.

DESCRIPTION

FIG. 1 is first top front perspective view of a cylinder showing a new design;

FIG. 2 is a first top rear perspective view of the cylinder illustrated in FIG. 1;

FIG. 3 is a second top rear perspective view of the cylinder illustrated in FIG. 1;

FIG. 4 is a second top front perspective view of the cylinder illustrated in FIG. 1;

FIG. 5 is a bottom front perspective view of the cylinder illustrated in FIG. 1;

FIG. 6 is a bottom rear perspective view of the cylinder illustrated in FIG. 1;

FIG. 7 is a front view of the cylinder illustrated in FIG. 1;

FIG. 8 is a left side view of the cylinder illustrated in FIG. 1;

FIG. 9 is a rear view of the cylinder illustrated in FIG. 1;

FIG. 10 is a right side view of the cylinder illustrated in FIG. 1;

FIG. 11 is a top view of the cylinder illustrated in FIGS. 1; and,

FIG. 12 is a bottom view of the cylinder illustrated in FIG. 1.

The broken lines shown for the purpose of illustrating parts of the cylinder and form no part of the claimed design.

1 Claim, 12 Drawing Sheets
